UNITED STATES PATENT OFFICE.

FRANK B. WENTWORTH AND LOUIS F. CLAUSING, OF LOS ANGELES, CALIFORNIA.

RADIATOR.

1,138,819.

Specification of Letters Patent. Patented May 11, 1915.

Application filed January 12, 1914. Serial No. 811,591.

To all whom it may concern:

Be it known that we, FRANK B. WENTWORTH and LOUIS F. CLAUSING, citizens of the United States, residing at Los Angeles, in the county of Los Angeles and State of California, have invented a new and useful Radiator, of which the following is a specification.

This invention relates to a radiator for use in connection with internal combustion engines, and one of the main objects of the invention is to provide a simple and economical construction which will give a large size of tube for the passage of water, and to also provide corrugations in the strips forming the walls of the water tubes, in such a way that a greatly extended length of tube is produced, giving the maximum cooling effect.

Another object is to provide a construction which will permit a flexibility of the parts, thereby avoiding leakage caused from strains.

Referring to the drawings: Figure 1 is a front elevation of a radiator. Fig. 2 is a side elevation of a portion of the radiator. Fig. 3 is a section on line x^3-x^3 , Fig. 2. Fig. 4 is a plan view partly in section of a portion of the radiator. Fig. 5 is a front elevation of a water tube unit. Fig. 6 is a side elevation of a spacing plate. Fig. 7 is a front elevation of a corrugated plate partly broken away, before being formed into either a spacing plate or water tube plate. Fig. 8 is a side elevation in detail of one of the plates forming a water tube. Fig. 9 is a side elevation of another plate forming the other member of the water tube. Fig. 10 is a perspective view in detail of a corrugated plate before being formed into either a water tube plate or a spacing plate.

In the present embodiment two forms of plates are employed, each plate first being formed in a suitable machine, as a simple corrugated plate 1, shown in detail in Figs. 7 and 10. From this simple form each of the different forms of plates are produced. Two of plates 2 and 3 shown respectively in Figs. 8 and 9 are formed to constitute the two members of a water tube, and a plate form 4 shown in Fig. 6, is employed as a spacing plate. The water tube plate 2 is changed from the simple corrugated plate 1 shown in Fig. 10, to its form shown in Fig. 8, by placing it in a press, together

with the water tube plate 3, these two plates being nested or laid together in such a way that the convex projections of each plate are in register with the concave portions of the opposite plate and a strip of metal, not shown, is laid between the two plates transversely to the corrugations of the plates, so that when the dies of the press come together, the corrugated portions along each side of the plates are brought into close and perfect union with each other, while the center portions are kept apart from each other by the interposed strip of metal which is then withdrawn, thus leaving a water conduit 5 between the two plates 2 and 3, extending transversely of the corrugations, the water conduit having a cross sectional area of varying shape and dimensions. The cross sectional area of the water conduit thus formed is not actually reduced to the elongated slot-like aperture 5 seen in Fig. 4, this slot-like aperture being substantially the shape of the strip of metal which had been laid between the plates to keep them from coming together, but the conduit is wider than this and longer, on account of the peculiar formation resulting from the corrugations in the two plates which go to form the water tube unit. Thus in Fig. 4 the maximum horizontal width of the water conduit extends from the wall a of plate 2 to the wall b of plate 3. These two walls converge toward each side of the plates 2 and 3 as at c and d , and the plates 2 and 3 are in perfect union with each other along the portions 8. An absolutely perfect fit along the edges at e between the two plates is secured by reason of the fact that at this point, the intermeshing corrugations, which are already in fairly good fit, are both subjected simultaneously to the action of the same dies, with the result that if there is any inequality in the shape of the dies at any point, both plates 2 and 3 will both be pressed to conform to such irregularities, so that both will exactly fit each other. This perfect union at this point is very important, as it enables the two plates to be perfectly soldered together at these contacting points and entirely prevents leakage, besides giving great strength to the water tube unit thus formed.

By referring to Fig. 3, the varying shape of the water tube at different vertical sections is shown. Thus in the bottom section is shown the tortuous nature of the water

passage consisting of the central unobstructed passage 5, with staggered lateral chambers 6, this section being taken directly through the center of the water tube, as will be seen by referring to the section line in Fig. 2. These convolutions in the water passage greatly increase the area of radiating surface to which the water is subjected in passing through the water tube, and give a maximum radiating effect. In the next uppermost portion of the sectional view, the water passage 5 is constricted at intervals, due to the peculiar angle of the corrugations, and this section of the water tube which lies at each side of the central portion of the conduit, gives additional radiating surface. The cross sectional area of this part gradually diminishes until it vanishes entirely at the point where the two plates come together as at e.

The water tube units are assembled together with the conduits 5 extending vertically and the convex projections of one water tube are exactly in register with the concave portions of the next water tube unit, but between the two units is a spacing plate 4, as clearly shown in Fig. 3, the convex projections of the spacing plate 4 touching the convex projections of the water tube unit, which thus provides air passages 7 which extend transversely to the water conduits 5. Each spacing plate 4 is originally a simple corrugated sheet 1, as in Fig. 7, but before being assembled is placed in a press and the central portions of the crest of the corrugations flattened somewhat, as at 8. It should be understood that this flattening is very much less than is given either plate 2 or 3, and the method by which it is flattened is different in that the operation is performed entirely by the dies directly against the corrugations, whereas in the case of the tube plates, the two plates were simultaneously placed in the press with the interposed strip of material. The flattened portions 8 of the plate 4 are so arranged that they exactly register with the flattened surfaces of the tube plates which are formed at the back walls of the cavities 6, and the flattened surfaces 8 of the spacing plates are soldered to the corresponding flattened surfaces of the tube plates, which gives a greater area of contact between the spacing plates and water tube plates soldered together so that perfect heat conductivity is obtained and corresponding heat radiating qualities are secured. The convex portions of the spacing plates are soldered to the convex portions of the water tube units, so that the radiator becomes a solid structure with all parts in perfect heat conducting relation, thereby insuring the maximum radiation.

The circulation of the water through the conduits 5 causes small cascades to form at the lateral recesses, which, together with the

great area of the surface with which the water comes in contact, gives the desired cooling effect. The inclined walls c, d, are at an angle to the air passages 7 and thus present surfaces against which the air must impinge and thereby give a greater radiating effect than where the walls are exactly parallel to the passage of the air and there is no impinging of the air against the walls.

By reason of the corrugated shape of the plates, it gives the metal a chance to bend between the joints where it is soldered, thus giving a great flexibility to the radiator, which obviates leakage, which is otherwise apt to occur when the radiator is strained.

What we claim is:

1. A water tube unit for radiators comprising a pair of opposed metal plates joined along their longitudinal edges, the plates having transverse corrugations extending across their entire width, and the convex portions of one plate projecting into and fitting the concave portions of the other plate, the crests of the corrugations being flattened, and the flattened portions extending a slight distance on each side of the longitudinal center of the section, and the plates being spread apart along their longitudinal center to provide a water channel.

2. A radiator comprising a plurality of water tube units, each unit consisting of a pair of similar plates formed with transverse corrugations extending across their entire width, the plates being secured together at their longitudinal edges with the convex portions of one plate projecting into and fitting the concave portions of the other plate, the inner crest portions of the corrugations being flattened on each side of the longitudinal center of the section, and the flattened portion of one section being disposed in spaced parallel relation to the flattened portion of the other section, thereby providing a water channel, and the unflattened portions of the corrugations forming blind lateral channels in communication at their inner ends with the first mentioned channel.

3. A radiator comprising a plurality of water tube units, each unit consisting of a pair of nested transversely corrugated plates, the corrugations extending entirely across said plates, the plates being united along longitudinal edges and being spread apart intermediate their united edges to form water conduits the crest portions of the corrugations being flattened intermediate their ends, the corrugations in the plates providing air passages transverse to the water conduits, and means secured between the units for spacing them apart and providing additional air passages.

4. A radiator comprising a plurality of water tube units, each unit consisting of a pair of nested, transversely corrugated

plates, the corrugations extending entirely across said plates, the plates being united along their longitudinal edges and being spread apart intermediate their united 5 edges to form water conduits, the crest portions of the corrugations being flattened intermediate their ends, said corrugations providing air passages transverse to the water conduits, and spacing plates between the 10 units, each spacing plate having corrugations with flattened central portions secured to corresponding intermediate portions of the water tube units, and the convex portions of the spacing plates being soldered 15 to the convex portions of the water tube unit.

5. A radiator comprising a plurality of water tube units arranged in parallel relation to one another, each unit consisting of 20 a pair of nested, transversely corrugated plates, the corrugations extending entirely across the plates, the central portions of the crests of the corrugations being flattened, and the plates being spread apart along the 25 line of their longitudinal centers to provide

a longitudinal water channel substantially rectangular in cross section, said channel extending at right angles to the corrugations, the plates converging from the said edges of the channel to their united longitudinal 30 edges, thus providing blind lateral channels communicant at their inner ends with the first mentioned channel, the concave portions on the exterior of the plates providing air passages, and a transversely corrugated 35 spacing plate between each pair of water units, crest portions of the corrugations of each spacing plate being flattened intermediate their ends, and the flattened portions being opposed to and secured to the exterior 40 flattened portions of the water units.

In testimony whereof, we have hereunto set our hands at Los Angeles, California this 5th day of January, 1914.
